UNITED STATES PATENT OFFICE.

GEORGE S. BARKENTIN, OF HARTFORD, ASSIGNOR TO P. & F. CORBIN, OF NEW BRITAIN, CONNECTICUT.

DESIGN FOR LOCK FACE-PLATES.

Specification forming part of Design No. **11,297**, dated July 15, 1879; application filed June 13, 1879.
[Term of patent 7 years.]

To all whom it may concern:

Be it known that I, GEORGE SLATER BARKENTIN, of Hartford, in the county of Hartford and State of Connecticut, have originated and produced a new and original Design for the Face-Plates of Locks, of which the following is a full, clear, and exact description, reference being had to the accompanying engraving, making part of this specification.

My design consists of sunken panels upon the face-plate of locks, within which are certain figures in relief, as hereinafter more fully described.

The bands *a a* are formed of zigzag lines, each outer division of which incloses a fan-shaped leaf, crossed by horizontal and perpendicular incised lines, and each inner division incloses a sunken leaflet. The remaining space is filled with the vertical flutes, as at *b*, narrow upright sunken panels with rows of quarter-foils in relief, as at *c c*, narrow upright sunken panels with matted ground, crossed by horizon-

tal lines, as at *d d d*, and the raised border *e*, upon which is formed a row of dentils, as shown.

The length and position of the flutes, and the narrow upright panels may vary, according to the length, width, and shape of the face-plate and the position of the bolts, as it will be seen that the design is applicable to locks of different sizes and with face-plates of flat, convex, or concave surfaces.

I claim as my invention—

The design for the face-plate of locks, consisting of the bands *a a*, dentils *e*, flutes *b*, and narrow upright panels, as at *c c* and *d d d*, combined and arranged substantially as shown and described.

Signed by me this 11th day of June, A. D. 1879.

GEORGE SLATER BARKENTIN.
